JACOB SPERLING, OF MOORES, PENNSYLVANIA, ASSIGNOR TO WESTINGHOUSE ELECTRIC & MANUFACTURING COMPANY, A CORPORATION OF PENNSYLVANIA

SIDE-WALL TUYÈRE

Application filed December 8, 1928. Serial No. 324,770.

My invention relates to stoker fired furnaces and particularly to apparatus of this character in which tuyère structures are disposed along a wall of the furnace for supplying air to the combustion chamber for supporting combustion and for preventing the formation of clinker on the furnace wall; and it has for an object to provide apparatus of this character which is of improved construction and arrangement of parts.

From the view point of assembly and repair, it is desirable that the so-called "side wall tuyère" be formed independently of the furnace side wall and be supported entirely by the stoker structure. In certain constructions heretofore known to me, the side wall tuyère has been in the form of an A in cross section, one leg of the A being supported by the retort side wall and the other leg being supported by an additional wall disposed adjacent the furnace side wall. This form is very expensive both for the reason that it is necessary to provide the additional wall structure for supporting the other leg of the A, and also for the reason that the extra metal required to provide said other leg is not justified by the increased efficiency of the stoker.

In other constructions known to me, instead of using the A form of tuyères, upwardly-inclined plate-like tuyères have been provided which extend from the upper edges of the side walls of the extreme retorts to the furnace side wall. These tuyères are supported by angle bracket constructions, the horizontal legs of which extend from the retort side wall to the furnace side wall and the vertical legs extend upwardly along the furnace side wall. In the latter construction, some additional structure has to be provided for supporting the angle bracket, such additional structure being either another wall disposed adjacent the furnace wall; or another angle bracket carried by the retort side wall and engaging the horizontal leg of the main bracket. Obviously, the additional supporting structure results in additional cost.

More particularly, therefore, an object of this invention is to provide a side wall tuyère structure which is durable, easy to in-

stall and to replace, comparatively cheap to manufacture, and one which is composed of a minimum number of parts.

These and other objects are effected by my invention, as will be apparent from the following description and claims taken in connection with the accompanying drawings, forming a part of this application, in which:

Fig. 1 is a transverse sectional view through a stoker fired furnace constructed in accordance with my invention;

Fig. 2 is an enlarged longitudinal sectional view taken on the line II—II of Fig. 1, certain of the furnace parts being omitted;

Fig. 3 is an enlarged transverse sectional view on the line III—III of Fig. 2, certain of the parts being omitted and others being broken away;

Fig. 4 is an enlarged longitudinal sectional view taken on the line IV—IV of Fig. 1 and showing the rear of a series of tuyères constructed in accordance with my invention;

Fig. 5 is an enlarged detail view of the face of a pair of the side wall tuyères;

Fig. 6 is an enlarged detail view showing the rear side of the side wall tuyères shown in Fig. 5; and,

Fig. 7 is a sectional view taken on the line VII—VII of Fig. 2.

According to a preferred embodiment of my invention, which is shown on the accompanying drawing, I provide a side wall tuyère which is supported entirely by the retort side wall and extends upwardly and towards the adjacent furnace side wall to form a cover for the side wall air box, which latter is defined by the retort side wall and furnace side wall. The tuyère is provided with a downwardly-extending leg portion which lies closely adjacent the retort side wall. A clamping plate engages the tuyère, and means is provided for detachably securing together the clamping plate, leg portion of the side wall tuyère and adjacent retort side wall.

Referring now in detail to the construction shown in the accompanying drawing and particularly to Fig. 1, it will be observed that I have shown a furnace having a pair of upright side walls 10 and 11, an upright

100

front wall 12 and a horizontally-extending wind box floor 13. The rear wall of the furnace has been omitted as its presence on the drawing is not deemed necessary to an understanding of the present invention.

5 A stoker structure 14 extends transversely across the furnace and divides the furnace into a combustion chamber 15 and an air chamber or wind box 16. Air under pressure is supplied to the air chamber by suitable conduits 17, 17 extending within openings in the wind box floor 13.

10 The stoker structure comprises vertical marginal wall elements 18 and 19 disposed adjacent to and in spaced, substantially parallel relation with the furnace side walls 10 and 11, respectively; pairs of intermediate wall elements 20, 20, 21, 21 and 22, 22 arranged in parallel relation with the marginal wall elements; and bottom wall elements 23, 24, 25 and 26 extending between each marginal wall element and the adjacent wall element of the adjoining pair of intermediate wall elements, and between the several pairs to form retorts 27, 28, 29 and 30.

15 The marginal wall elements and the intermediate wall elements are supported by angle members 31, 31 which latter are supported at their ends by any suitable part of the furnace structure. Each angle member has a horizontal flange 32 which extends beneath and supports its respective wall element and a vertical flange 33 which extends along the side of that wall element. Bolts 34, 34 serve to secure the vertical flanges of the angle members to the wall elements. A strengthening bar 35 extends transversely of the stoker structure and is secured by bolts 36, 36 to the horizontal flanges of each of the angle members.

20 The marginal wall element 18 forms, in conjunction with the furnace side wall 10, a side wall air box 40; and the marginal wall element 19 forms, in conjunction with the furnace side wall 11, a side wall air box 41. The pairs of intermediate wall elements 20, 20, 21, 21 and 22, 22 form intermediate air boxes 43, 44 and 45, respectively. All of the air boxes are in open communication, at 25 their lower ends, with the air chamber 16.

25 As is common with stokers of this type, overlapping tuyère blocks 46, 46 are supported by each pair of intermediate wall elements. The tuyère blocks form covers for the intermediate air boxes and provide grate surfaces for supporting and supplying air to the fuel.

30 In operation, coal is fed from a hopper 47 and longitudinally of each retort by primary and secondary rams 48 and 49, respectively. The coal becomes heated within the retorts and the gases are driven off, which gases rise to the upper surface of the fuel bed and are burned. The resulting coke is forced to the 35 upper surface of the fuel bed and over on to

the tuyère rows, where it comes into contact with the air and is burned.

I provide a series of tuyères 50, 50 of improved form, along each side wall of the furnace, which tuyères supply air for combustion to the marginal retorts, and prevent the formation of clinker on the side walls of the furnace. The tuyères are disposed in side-by-side relation and extend upwardly from the marginal wall elements 18 and 19 and 75 toward the furnace side walls 10 and 11, respectively, thereby providing covers for the side wall air boxes 40 and 41.

80 Improved means is provided for supporting and securing the side wall tuyères 50, 50. Each of the tuyères is provided with a downwardly-extending leg portion 51 which lies flat against its respective marginal wall element. The leg portion is so formed with respect to the upper portion thereof, as to provide a shoulder or ledge portion 52 which rests upon and is supported by the upper edge of the marginal wall element.

85 The leg portion of each tuyère is firmly secured to its respective marginal wall element 90 by means of a clamping plate 53 and bolts 54, 54 extending through the clamping plate, leg portion and marginal wall element. A separate clamping plate is provided for each tuyère. The lower portion of each clamping 95 plate extends downwardly and is secured to the vertical flange 33 of the angle member 31 by the bolts 34, 34, which latter also secure the marginal wall element to the angle member.

100 Each clamping plate 53 is provided with an upwardly-extending arcuate portion 55 which engages and supports the underside of the tuyère. The clamping plates are also provided with strengthening ribs 56, 56.

105 The tuyères of each series are joined together by a modified form of ship-lap joint. Each of the tuyères is provided with projections 57, 57 and recesses 58, 58, which cooperate with recesses and projections, respectively, of adjacent tuyères to form the joint.

110 Both of the projections on any one tuyère extend from either the front face or the rear face of that tuyère. As shown in Fig. 7, the projections on tuyère 50^a, tuyère 50^b and tuyère 50^c are all flush with the front face, while the projections 57, 57 on tuyère 50^d and tuyère 50^e extend from the rear face. The reason for this construction is to provide a joint which permits the removal of any one 115 tuyère without disturbing any more than one of the adjacent tuyères. If either tuyère 50^a or tuyère 50^c is to be removed, all that is required is that one of the adjacent tuyères be first removed. Obviously, if either tuyère 50^a, 50^b, or 50^c requires removal, all that is required is the removal of the bolts 34, 34 and 54, 54 and clamping plate of that particular tuyère.

120 The tuyères 50, 50 are preferably composed 130

5 of a single casting. The front face, with the exception of the air-emitting openings, is formed smooth so as to preclude the adhering of clinker thereto. The rear face of the tuyères are provided with cooling ribs 60, 60, (see Figs. 4 and 6).

10 In constructing the tuyères 50, 50 with depending leg portions which lie flush against the marginal wall elements 18 and 19 and in securing these tuyères to the marginal wall elements by the clamping plate bolts 34, 34 and 54, 54; I provide an extremely simple form of side wall tuyère, which does away with the necessity of providing expensive additional supporting structure. In addition, 15 my improved form of tuyère can be quickly and easily installed and removed.

20 While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed 25 by the prior art or as are specifically set forth in the appended claims.

What I claim is:

30 1. In combustion apparatus, the combination of a furnace including upright walls; a stoker disposed within the furnace and including a retort having a side wall disposed in spaced, substantially parallel relation with respect to one of the furnace walls; a plurality of upwardly-inclined tuyères bridging the space between said retort side wall and said one furnace wall; each of said tuyères including a downwardly-extending leg portion having a side arranged closely adjacent the side of the retort side wall; and detachable means for rigidly securing the leg portions of the tuyères to the retort side wall, whereby the tuyères are supported independently of said one furnace side wall.

40 2. In combustion apparatus, the combination of a furnace including upright walls; a stoker arranged within the furnace and including a retort having a side wall disposed in spaced, substantially parallel relation with respect to one of the furnace walls; a plurality of upwardly-inclined tuyères bridging the space between the retort side wall and said one furnace wall; each tuyère including a leg portion disposed at the side of said retort side wall adjacent said furnace wall; clamping plates engaging the leg portions; and detachable means for rigidly securing together said retort side wall, leg portions and said clamping plates, whereby the tuyères are supported by the retort and independently of said one furnace side wall.

45 3. In combustion apparatus, the combination of a furnace including upright walls; a stoker including a retort disposed in spaced, substantially parallel relation with respect to one of the furnace walls; said retort com-

5 prising a pair of vertically-arranged side walls disposed in spaced, substantially parallel relation to one another and to said one furnace wall, a bottom wall extending between the retort side walls and a pair of angle members for supporting the retort walls; the angle members being disposed at the two lower corners of the retort and having vertical flanges arranged closely adjacent the outside of the retort side wall; a plurality of upwardly-inclined tuyère members bridging the distance between the retort side wall adjacent said one furnace wall and such furnace wall; each of the tuyères including a downwardly-extending leg portion disposed adjacent the side of the retort side wall adjacent said furnace wall; clamping plates engaging both said leg portions and said vertical flange of the adjacent supporting angle member; and detachable means for rigidly securing together the retort side wall, the leg portions of the tuyère members, the vertical flange of the adjacent angle member and the clamping plates, whereby the tuyères are supported by the retort and independently of said one furnace wall.

6 4. In combustion apparatus, the combination of a furnace including upright walls; a stoker disposed within the furnace and including a retort having a side wall disposed in spaced, substantially parallel relation with respect to one of the furnace walls; a plurality of upwardly-inclined tuyères bridging the space between said retort side wall and said one furnace wall; each of said tuyères having a ledge portion resting upon the upper portion of the retort side wall and a downwardly-extending leg portion having a side thereof disposed closely adjacent the side of the retort side wall; and detachable means for rigidly securing the leg portions to the retort side wall, whereby such tuyères are supported by the retort side wall and independently of said one furnace wall.

7 5. In combustion apparatus, the combination of a furnace including a pair of upright side walls; a mechanically-operated stoker disposed within the furnace and comprising a plurality of alternately-arranged retorts and tuyère rows extending from the front to the rear of the furnace; the retort adjacent each furnace side wall including a side wall disposed in spaced, substantially parallel relation with respect to such furnace side wall, and forming in conjunction with such furnace side wall a side wall air box; a plurality of side wall tuyères disposed in abutting side-by-side relation and extending upwardly from each aforementioned retort side wall and toward the adjacent furnace side wall to form a cover for the respective side wall air box; each of the side wall tuyères including a downwardly-projecting leg portion disposed adjacent the side of the adjoining retort side wall; and detachable means for rig-

idly clamping the leg portions to the retort side walls, whereby the tuyères are supported by the retort side walls and independently of the adjacent furnace walls.

6. In combustion apparatus, the combination of a furnace including a pair of upright side walls; a unitary underfeed stoker structure dividing the furnace into combustion and air chambers and including two marginal wall elements disposed, respectively, in spaced, substantially parallel relation with the furnace side walls, pairs of intermediate wall elements, and bottom wall elements extending between the marginal wall elements and the adjacent wall element of the adjoining pairs and between the several pairs to form retorts; said pairs of intermediate wall elements and each of said marginal wall elements in conjunction with the adjacent furnace side wall, defining respectively a plurality of intermediate and side wall air boxes in communication with said air chamber; tuyères supported by the upper portions of the pairs of intermediate wall elements and forming a cover for the intermediate air boxes; a plurality of side wall tuyères arranged in abutting side-by-side relation and extending upwardly from each marginal wall element and inwardly toward the adjacent furnace side wall to provide covers for the side wall air boxes; each of the side wall tuyères including a downwardly-extending leg portion disposed within the side wall air box and closely adjacent the side of the marginal wall element; and detachable clamping means for rigidly securing together the leg portions and the marginal wall elements, whereby the side wall tuyères are supported by the marginal wall elements and independently of the furnace side walls.

7. In combustion apparatus, the combination of a furnace including a pair of upright side walls; a unitary underfeed stoker structure dividing the furnace into combustion and air chambers and including two marginal wall elements disposed, respectively, in spaced, substantially parallel relation to the furnace side walls, pairs of intermediate wall elements, and bottom wall elements extending between the marginal wall elements and the adjacent wall elements of the adjoining pairs and between the several pairs to form retorts; said pairs of intermediate wall elements and each of said marginal wall elements in conjunction with the adjacent furnace side wall, defining respectively a plurality of intermediate and side wall air boxes in communication with said air chamber; tuyères supported by the upper portions of the pairs of intermediate wall elements and forming a cover for the intermediate air boxes; a plurality of side wall tuyères arranged in abutting side-by-side relation and extending upwardly from each marginal wall element and inwardly toward the ad-

jacent furnace side wall to provide covers for the side wall air boxes; each of the side wall tuyères including a downwardly-extending leg portion disposed within a side wall air box and closely adjacent the side of its respective marginal wall element; a clamping and supporting plate disposed within each side wall air box and engaging the side wall tuyères; and detachable means for rigidly securing together each side wall tuyère, its adjacent marginal wall element and clamping plate, whereby the side wall tuyères are supported by the marginal wall elements and independently of the furnace side walls.

In testimony whereof, I have hereunto subscribed my name this 3rd day of December, 1928.

JACOB SPERLING.
